(57) CLAIM

The ornamental design for a duck blind, as shown and described.

DESCRIPTION

FIG. 1 is an isometric view of a duck blind showing my new design. The duck blind is shown in the closed position.

FIG. 2 is an isometric view of a duck blind shown with one section in the open position.

FIG. 3 is a top view of a short version of the duck blind.

FIG. 4 is a front end view of the short version of the duck blind.

FIG. 5 is a left side view of the short version of the duck blind.

FIG. 6 is a right side view of the short version of the duck blind.

FIG. 7 is a rear end view of the short version of the duck blind; and,

FIG. 8 is a bottom view of the short version of the duck blind. The broken lines are for illustrative purposes only and form no part of the claimed design.
